Inventor,

David S. Anderson

UNITED STATES PATENT OFFICE.

DAVID S. ANDERSON, OF McGRAWVILLE, NEW YORK.

SLEIGH.

SPECIFICATION forming part of Letters Patent No. 378,821, dated February 28, 1888.

Application filed January 17, 1888. Serial No. 260,981. (No model.)

To all whom it may concern:

Be it known that I, DAVID S. ANDERSON, a citizen of the United States, residing at McGrawville, in the county of Cortland and State 5 of New York, have invented certain new and useful Improvements in Sleighs; and I do hereby declare that the following is a full, clear, and exact description of the same, reference being had to the annexed drawing, making a 10 part of this specification, and to the letters and figures of reference marked thereon.

This invention relates to certain new and useful improvements in sleighs, and has for its object the production of a light pleasure or heavy-draft sleigh, in which those violent jars caused by obstacles, depressions, &c., in the road are 15 nearly or quite avoided, and one in which short turns may be made with ease and safety and the sleigh less liable to be upset.

20 To the above ends, and to such others as the invention may pertain, the same consists in the peculiar combinations and the novel construction, arrangement, and adaptation of parts, all as more fully hereinafter described, 25 shown in the drawings, and then particularly pointed out in the claims.

The invention is clearly illustrated in the accompanying drawing, which represents a side view of a sleigh constructed in accordance with 30 my invention.

Referring to the drawing by letter, A designates the body of the sleigh, which may be of any approved construction and may be as ornamental as desired.

35 B designates the runners, which are formed in two parts, the adjacent parts of the two runners on each side of the sleigh being curved, as shown, and arranged to leave a space, C, between them. The curved ends *a* of the runners are secured to the sill *b* of the body A by 40 means of suitable bolts.

D is a suitable clip or tie connecting the two parts of the runner together, as shown. Depending from the central cross-bar, *c*, is a brace, 45 *d*, extending down to the clip D.

E is a brace-rod connecting the rear cross-bar, *f*, with the rear end of the runner, and F is a similar brace connecting the forward cross-beam, *g*, with the forward part of the runner.

50 *h* are curved brace-rods secured to the brace-rod E and connecting the same with the rear

part of the runner and the sill of the body, as shown. *i* are similar curved brace-rods at the forward part of the runner and secured to the brace-rod F by the lateral brace-rod G. 55

It will be seen that by the above construction when the sleigh passes rapidly through depressions or hollows there will be no violent pitching forward or backward, but, on the contrary, the sleigh will pass over or through 60 these places, and thus the disagreeable jerk and shock commonly felt under these circumstances is avoided; also, in turning around, the space C provides a passage for the snow which usually gathers at the center of the runner, thus avoiding strain on the gear and the danger of upsetting; also sliding, sluing, &c., so common to long runners and so annoying and many times dangerous, is in a great degree remedied. 70

I am aware that it has been proposed to construct a runner for attachment to the wheels of a vehicle whereby the same may be readily put upon runners in case of snow, said runner being arched between the wheels to lessen the 75 friction, and do not claim such as of my invention.

What I claim as new is—

1. The combination, with the sleigh-body, of a runner formed of two parts secured to the 80 sill of said body, with a space, C, between the adjacent running-surfacing thereof, substantially as described.

2. The combination, with the sleigh-body, of the runner formed in two parts secured to 85 the sill of said body and curved at their adjacent portion, with a space, C, between them, substantially as described.

3. The combination, with the sleigh-body and the cross-beams, of the runners having 90 their adjacent curved ends secured to said body, the clip D, the brace-rods E F, the curved braces *h* *i*, and the lateral brace G, all constructed and arranged substantially as described. 95

In testimony that I claim the above I have hereunto subscribed my name in the presence of two witnesses.

DAVID S. ANDERSON.

Witnesses:

A. G. BROOKS,
PERRIN H. McGRAW.
